(57) **CLAIM**

The ornamental design for a colored pencil, as shown and described.

DESCRIPTION

FIG. 1 is a front, right and top perspective view of a colored pencil, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a cross-sectional view of the colored pencil of FIG.

1, taken along section line 8-8 as depicted in FIG. 2.
The broken lines depict portions of the colored pencil that form no part of the claimed design.

1 Claim, 8 Drawing Sheets
